ATTORNEY

UNITED STATES PATENT OFFICE

139,441

DESIGN FOR A FLASHLIGHT OR LIKE ARTICLE

Joshua Gordon Lippincott, Scarsdale, N. Y., assignor to Guth, Stern & Co., Inc., a corporation of New York

Application June 2, 1944, Serial No. 113,839

Term of patent 14 years

(Cl. D48—24)

To all whom it may concern:

Be it known that Joshua Gordon Lippincott, a citizen of the United States and resident of Scarsdale in the county of Westchester and State of New York, has invented a new, original, and ornamental Design for a Flashlight or like article, of which the following is a specification, reference being had to the accompanying drawing, forming part thereof, in which

Fig. 1 is a perspective view of the flashlight showing my new design, and

Figs. 2 and 3 are bottom and front elevational views respectively, thereof.

I claim:

The ornamental design for a flashlight or like article, as shown.

JOSHUA GORDON LIPPINCOTT.
